CLAIM

The ornamental design for a bird feeder overspill tray, as shown and described.

DESCRIPTION

FIG. 1 is a top perspective view of the bird feeder overspill tray.

FIG. 2 is a top plan view thereof;

FIG. 3 is a bottom plan view thereof;

FIG. 4 is a right side elevation view thereof;

FIG. 5 is a left side elevation view thereof;

FIG. 6 is an end elevation view thereof;

FIG. 7 is an end elevation view thereof taken opposite FIG. 6; and,

FIG. 8 is an environmental top perspective view thereof. The broken line showing of a feeder and stand in FIG. 8 is not claimed.

1 Claim, 5 Drawing Sheets
